DESIGN FOR A PROJECTOR

Harold Osterberg and Kennard W. Harper, Buffalo, and William F. Peck, Snyder, N. Y., assignors to Spencer Lens Company, Buffalo, N. Y., a corporation of New York

Application August 27, 1940, Serial No. 94,642

Term of patent 14 years

To all whom it may concern:

Be it known that we, Harold Osterberg, Kennard W. Harper, and William F. Peck, citizens of the United States, residing at Buffalo, Buffalo, and Snyder, respectively, in the county of Erie and State of New York, have invented a new, original, and ornamental Design for a Projector, of which the following is a specification, reference being made to the accompanying drawings, forming a part thereof.

Fig. 1 is a side view of a projector embodying our design;

Fig. 2 is an end view of the projector shown in Fig. 1; and

Fig. 3 is a top plan view of the projector shown in Figs. 1 and 2.

We claim:

The ornamental design for a projector, substantially as shown.

HAROLD OSTERBERG.
WILLIAM F. PECK.
KENNARD W. HARPER.
